(57) CLAIM

The ornamental design for a shoe with heel, as shown and described.

DESCRIPTION

FIG. 1 is a perspective view of an embodiment of my new design for a shoe with heel;

FIG. 2 is a front view of the design of FIG. 1;

FIG. 3 is a back view of the design of FIG. 1;

FIG. 4 is a first side view of the design of FIG. 1;

FIG. 5 is a second side view of the design of FIG. 1;

FIG. 6 is a top view of the design of FIG. 1; and,

FIG. 7 is a bottom view of the design of FIG. 1.

The wavy lines represent surface shading.

The broken lines illustrate features of the shoe with heel that form no part of the claimed design.
